UNITED STATES PATENT OFFICE.

WARREN SNURE, OF WOOSTER, OHIO.

DISH-WASHING MACHINE.

1,329,863.

Specification of Letters Patent.

Patented Feb. 3, 1920.

Application filed May 27, 1919. Serial No. 300,229.

To all whom it may concern:

Be it known that I, WARREN SNURE, a citizen of the United States, residing at Wooster, in the county of Wayne and State 5 of Ohio, have invented a new and useful Dish-Washing Machine, of which the following is a specification.

My invention relates to improvements in dish-washing machines, and particularly to 10 that class which provides one or more receptacles for dishes adapted to be reciprocated within tanks of water; and its objects are, first, to provide simpler and more efficient means for hoisting and reciprocating 15 the receptacles; second, to provide laterally adjustable seats or tables for the receptacles; and, lastly, to provide means for actuating the reciprocating mechanism in part by motor power; all of which objects 20 are accomplished by the devices hereinafter fully set forth and stated in the appended claim.

My invention is illustrated by the accompanying drawings in which similar letters 25 and figures of reference indicate like parts. Referring thereto, Figure 1 is a view in plan of a dish-washing machine embodying my invention; Fig. 2 is an elevation of the machine showing the hoisting mechanism 30 partly in section; Fig. 3 is a detail view partly in section of the hoisting mechanism; and Fig. 4 is a detail form of means for reciprocating the standard.

In the drawings, A, B and C are the machine frame, water tanks and dish receptacle, respectively, and are substantially such as heretofore used, and no claim is made thereto specifically. D is the upper member of the standard which forms a part 35 of the hoisting apparatus, and carries an arm 1 as a crane from which the dish receptacle C is removably suspended by a suitable cord or chain 20, and has a toothed rack 2 secured thereto longitudinally, and is provided with an anti-friction pulley 3 at its 40 lower end, as shown in Fig. 2.

E is the middle and lower member of the standard, preferably tubular, and of a size large enough to admit said upper member D 45 within its bore loosely so as to freely reciprocate endwise therein. A longitudinal groove 15 is cut therein of sufficient width and length to permit said rack 2 to reciprocate freely therein from end to end of said 55 rack.

A gear supporting band or collar F is se-

cured around the top of the said larger member, and a pinion 8 is mounted therein, and adapted to engage the teeth of said rack within said groove 15, said pinion being operable by the hand crank 9 upon its extended shaft. An anti-friction pulley 7 is also mounted in said collar above said pinion, as shown in Fig. 4, and is adapted to bear against the adjacent side of said upper member, to reduce friction at said point, and a dog 6 is fitted thereto so as to hold member D in elevated position, at pleasure.

A bottom end portion I of said member E is fitted to reciprocate within and through 70 a support 10 secured to said tanks, or otherwise, a limited distance, as shown in Fig. 4. This reciprocation is accomplished ordinarily by means of the hand lever G, which is pivotally mounted on a support 12 near 75 the base of the machine frame A by pivot g; a lateral arm 5 of said lever G is adapted to pivotally engage the lower end of said member I by means of a vertical strap 4, and is resiliently held in position elevated by a 80 spiral spring J connected thereto and to the upper part of said frame, as shown in Fig. 4.

Means are also provided for actuating 85 said standard vertically by motor power, if desired. I accomplish this by substituting for said hand lever and its connections, the horizontal bar H, which is mounted on a pivot h on support 11, and its short end connected to said strap 4, either in connection with, or independently of said hand lever 90 arm 5, and its outer end is provided with a slot 18 adapted to operatively engage a shaft 17 and motor driven mechanism K, in a well known way.

Receptacle seats L L' are mounted at one 95 or both ends of the frame A, and adapted to swing laterally on rotary posts 14, as shown in Fig. 1, and may be made of any desired shape or size; and a drainage orifice 13 permits the drip from the receptacle C to 100 escape into the adjacent tank. Their rotary movement is useful for shifting them to any desired lateral position to accommodate the desired position of the receptacle, and provides convenient room for placing either 105 washed or unwashed dishes thereon for handling.

The washing operation is as follows: Unwashed dishes, being properly placed in the receptacle C, the latter is elevated and 110 swung into position immediately above either of the tanks by the rotary move-

ment of the crane D, and then lowered into the tank by operating the hand lever 9, the dog 6 having been lifted for this purpose; the hand lever G is swung to the left in Fig. 5 1 by weight of the receptacle upon the member E, by means of the connecting link 4 and the lever arm 5. The receptacle may then be moved up and down in the water a limited distance by operating the hand lever 10 G, until the dishes are thoroughly cleaned, when it is again elevated by said lever and locked in said position by a fastener 16, whereupon the receptacle may be elevated 15 to a point above the tank, and swung sideways to rest upon one or the other of said seats L, as aforesaid.

Having thus fully described my invention, what I claim as new, and desire to secure by Letters Patent is—
20 In a dish-washing machine, the combination with a frame, water tanks mounted in said frame, and a receptacle for dishes in

relation thereto; of a hoisting and laterally shifting and vertically reciprocating mechanism for handling said receptacle, comprising a rotatable standard having a lateral arm adapted to swing sidewise thereon over said frame, said standard made of two parts, the upper part adapted to reciprocate vertically in the lower part a limited distance, means for reciprocating said upper part in said lower part, and thereby lengthening and shortening said standard, and means for manually reciprocating vertically said entire standard a limited distance, substantially as set forth. 25 30 35

In witness whereof, I have hereunto set my hand at Wooster, Ohio, this 9th day of April, 1919.

WARREN SNURE.

In presence of—

W.M. J. READ,

WALTER J. MOUGHEY.
